UNITED STATES PATENT OFFICE.

WILLIAM C. BRAY, OF NEWTON, MASSACHUSETTS.

DESIGN FOR A RIVET.

SPECIFICATION forming part of Design No. 27,568, dated August 24, 1897.

Application filed December 2, 1896. Serial No. 614,243. Term of patent 14 years.

To all whom it may concern:

Be it known that I, WILLIAM C. BRAY, of Newton, in the county of Middlesex and State of Massachusetts, have invented and produced a new and original Design for Rivets, of which the following, taken in connection with the accompanying drawings, is a specification.

Figure 1 of the drawings is a plan of a rivet, showing my design; Fig. 2 an elevation of the same, and Fig. 3 is a central vertical section of the same on line $x-x$ on Fig. 1.

The leading feature of my design consists in a rivet having a tubular cylindrical shank and a circular head having a smooth outer edge and a convex upper surface and a flat under surface, said outer convex surface having formed thereon in relief a representation of an eight-pointed star, comprising a central hub having a convex outer surface and eight points radiating therefrom at equal distances from each other and of equal lengths and having their outer surfaces rounded or curved transversely, as shown.

In the drawings, II is the rivet-head, the

main body of the outer surface of which is convex and having a smooth circular outer edge and a flat inner face, from which projects the shank or attaching member S.

The convex outer surface of the head II 30 has formed thereon a representation of an eight-pointed star raised above the convex outer surface of the main body of the head and comprising the central hub h , having a convex outer surface, and the eight radiating 35 points or arms p of equal lengths and having their outer surfaces rounded or curved transversely, as shown.

What I claim is—

The design for a rivet substantially as here- 40 in shown and described.

In testimony whereof I have signed my name to this specification, in the presence of two subscribing witnesses, on this 28th day of November, A. D. 1896.

WILLIAM C. BRAY.
